GLASSWARE FORMING MACHINE

Carl W. Schreiber and John E. McLaughlin,
Alton, Ill., assignors to Owens-Illinois Glass
Company, a corporation of Ohio

Application May 21, 1932, Serial No. 612,724

3 Claims. (Cl. 49—5)

The present invention relates to improvements in glassware forming machines and more particularly to means for temporarily closing the charging opening of a suction type blank mold following the usual charge severing operation.

An object of the invention is the provision of mold closing cups individual to the blank molds on a glassware forming machine, said cups being movable into operative and inoperative positions independently of the charge severing means.

Another object is the provision of a self aligning cup of the above character which floats in its support or carrier and may because of this floating feature, effectively close and seal the charging opening of the corresponding blank mold.

A further object is the provision of means whereby a mold closing cup of the above character can be adjusted to operate at various elevations as required by blank molds of different lengths.

Other objects will be in part apparent and in part pointed out hereinafter.

In the drawings:

Fig. 1 is a sectional elevational view illustrating one embodiment of the present invention mounted upon one mold group of a suction type glassware forming machine.

Fig. 2 is a plan view of the invention.

Fig. 3 is a detail side elevational view thereof.

Fig. 4 is a sectional elevational view showing in detail a control valve.

Fig. 5 is a view showing the position of the cup lifting cam relative to the forming machine and revolving pot.

Fig. 6 is a sectional view taken along the line VI—VI of Fig. 2.

Fig. 7 is a transverse sectional view taken along the line VII—VII of Fig. 3.

Fig. 8 is a sectional view taken along the line VIII—VIII of Fig. 3.

Fig. 9 is a sectional view taken along the line IX—IX of Fig. 3.

Fig. 10 is a detail sectional view showing the cup and cup carrier or support construction.

Fig. 11 is a view somewhat similar to Fig. 10 showing the cup raised into engagement with the bottom of a blank mold.

Fig. 12 is a fragmentary plan view showing means for adjusting the cup laterally on its carrier.

Fig. 13 is a sectional view taken along the line XIII—XIII of Fig. 12.

In more or less general terms the present invention consists of mold closing cups individual to the blank molds of a suction type forming

machine such for example as shown in LaFrance Patent 1,348,365, dated August 3, 1920, to which reference may be made for details of construction of the machine. Each cup is suitably mounted for movement radially of the machine between operative and inoperative positions and is so supported upon a carrier that it is free for limited floating movement whereby accurate alignment and sealing contact between the cup and mold will be assured.

The machine with which the present invention is illustrated comprises a series of mold groups 15 mounted upon individual frames 16 or arms which together make up a mold carriage mounted for continuous rotation about the vertical axis of a central column 17. Movement of the mold carriage brings the mold groups 15 successively to a charging position where the blank molds 18 gather mold charges from a supply body 19 of molten glass contained in a revolving pot 20 or other receptacle. Each mold group 15 includes in addition to the blank mold 18, a neck mold 21 which is arranged on the lower side of a head casting 22. This head casting and the blank and neck molds together with a plunger 23, plunger operating mechanism 24, and an air pressure control valve 25, are adapted for up and down movement relative to the mold carriage 16, such movement being effected by mechanism including a bell crank lever 26 and cam mechanism 27 associated therewith. The bell crank lever provides connection between the cam mechanism and a dipping frame 28 upon which the molds and other elements directly associated therewith are mounted. A counter weight 29 and coil spring 30 associated therewith and arranged with the central column 17, are connected through a lever 31 to said dipping frame 28. The effect of the counter weight and spring is to approximately counter-balance the weight of the frame 28 and elements supported thereon.

The blank mold 18 which consists of two sections is adapted to be operated by means including a piston motor 32, said motor driving a rack 33 which is connected through suitable mechanism to the mold sections. The neck mold 21 may be alternately opened and closed by an air motor 34 operating through suitable mechanism.

Below the blank forming unit there is provided a finishing mold 35 mounted upon a suitable carrier 36 which is adapted to be moved up and down periodically. Details of construction which are not fully set forth herein and in fact do not constitute a part of the present invention may be

more fully understood by reference to the La-France patent above identified.

Each blank mold 18 as it is brought over the receptacle 20 is lowered into contact with the supply body 19 of molten glass and a charge of glass is drawn into the mold through the charging opening at the lower end, filling both the blank and neck mold cavities. The mold is then lifted away from the supply body of glass and a knife 37 is operated to separate the gathered mold charge from said supply body. Following this charge severing operation it is customary and has been found essential to the production of quality glassware to compact the glass making up the mold charge, through the application of air under pressure to the upper end of the mold charge by way of the valve 25. In this connection it will be understood that the plunger 23 is first withdrawn by means of its operating mechanism 24 and the valve 25 positioned over the passageway in the head casting 22 through which the plunger has been withdrawn. Application of air under pressure to the upper end of the gathered mold charge materially increases the density of the gathered glass forming a comparatively solid blank and in addition tends to cause extrusion of the glass through the charging opening at the lower end of the blank mold. Ordinarily, a flat baffle plate or cup-like closure forming an integral part of the cut-off unit is positioned over this charging opening in advance of this compression below to prevent such extrusion of the glass and smooth or iron out the roughened portions created by the cut-off knife.

According to the present invention there is provided a closure cup which in a sense floats so that it is capable of multi-directional movement and as a result will, at every operation, be brought into proper engagement with the charging end of the mold. Thus effective sealing contact between the closure cup and mold may be obtained even though they are not accurately aligned prior to their being brought together. The specific construction may be substantially as follows: A closure cup 40 is suitably supported at the outer end of a horizontal carrier 41 which is adapted to be reciprocated horizontally by a piston motor 42. The entire unit including the cup carrier and piston motor (Figs. 1 and 2) may be fixed to a frame 43 which is mounted upon a vertical slide 44. This slide is attached to one of the frames 16. By means of a hand wheel 45, shaft 46, meshing bevel gears 47, and a vertical shaft 48 which is threaded through one of the bevel gears and connected to the frame 43, said frame and the elements supported thereon including the closure cup 40, may be adjusted vertically to compensate for variations in the lengths of the blank molds. Details of construction of this feature may be more fully determined by reference to the LaFrance patent referred to above.

The closure cup 40 is of circular form and includes a continuous upstanding wall 50 having a channel 51 in its flat upper surface adapted for sealing contact with the lower end of the blank mold 18. The side walls of the cup taper downwardly forming an inclined bearing surface designed for engagement with bearings 52, said bearings being arranged in an annular series within a receiver 53. Sufficient clearance is provided beneath and around the cup 40 to permit multi-directional movement thereof relative to the receiver 53 in the event such movement is essential to proper alignment of the cup and corresponding blank mold. The receiver 53 forms

part of a cup holder 54 which is attached to one end of the carrier 41. A depending sleeve 55 on the lower side of the receiver 53 telescopes within a sleeve 56. These sleeves are slidably connected together by a pin 57 and normally held in their maximum extended positions by means of a coil spring 58 which encircles said pin 57. These sleeves are mounted for vertical movement in a guide 59 in which the outer sleeve 56 is keyed to prevent rotation thereof. A cam roll 60 at the lower end of the outer sleeve 56 is adapted for periodic engagement with the upper side of a stationary cam 61 (Figs. 5 and 11). It will be observed that this cam 61 is so positioned that it moves the cup upwardly into engagement with the corresponding blank mold very shortly after the charging operation. An arm 62 upon the outer end of which the guide 59 is formed is secured by bolts 63 or the like to the carrier 41.

This carrier 41 by means of which the closure 20 cup is alternately projected and retracted to and from an operative position beneath the blank mold, includes an inverted channel iron bar 64 riding and guided between pairs of vertically spaced anti-friction rollers 65. The upper rollers 25 65 are journaled on shafts 66 which in turn are supported in bearings 67 forming a part of the frame 43. The lower rollers 65 are carried by shafts 68 supported in bearings 69 on the upper side of a cylinder 70 of the piston motor 42.

This piston motor 42 which reciprocates the carrier 41 and therewith the cup 40, includes the horizontal cylinder 70, a piston 71 therein, and a piston rod 72 attached to said piston 71 and extending through the outer end of the cylinder 35 where it is suitably connected to the holder 54. Cushioning devices 73 of well known conventional form are provided at the opposite ends of the cylinder 70 for obvious reasons. A pair of air pressure supply pipes 74 connected to the opposite 40 ends of the motor cylinder 70 lead to a control valve 75 (Figs. 1 and 4) which is connected to a main supply pipe 76. This control valve 75 includes a cylinder 77 to the center of which the supply pipe 76 is connected and to the opposite 45 end portion of which the branch pipes 74 are connected. A slide valve 78 in the form of a piston, is arranged within the cylinder 77 and adapted due to periodic movement thereof to provide communication between the supply pipe 76 50 and the branch pipes 74 one at a time. This valve 78 is connected by means of a push rod 79 to a cam roll 80 which runs in a stationary continuous cam 81. This cam 81 operates the valve 78 in timed relation with movements of the machine. 55 An exhaust passageway 82 in the valve 78 and rod 79 is adapted for register with the branch pipes 74 one at a time so that air pressure will be released from one end of the piston motor 42 while pressure is being built up at the other end thereof. 60

From the above it is apparent that in operation the blank molds are brought successively to a position over the receptacle 20 and there lowered into contact with the supply body of glass. A mold charge is gathered by suction and the blank 65 mold lifted away from the glass. Thereupon the cut-off knife 37 is operated to sever the gathered mold charge from the supply body. This knife is then withdrawn from beneath the mold and immediately thereafter the valve 78 is moved 70 to the outer end of the cylinder 77 so that air under pressure is admitted to the inner end of the piston motor 42. In this manner the carrier 41 is projected sufficiently to bring the closure cup 40 into substantial if not accurate, alignment

with the corresponding blank mold. Movement of the mold carriage about the central column 17 brings the cam roll 60 at the lower end of the cup holder 54 into engagement with the upper 5 side of the stationary cam 61. This results in upward movement of the receiver 53 and closure cup 40 a sufficient distance to effect sealing contact between said cup and the lower end of the blank mold. By the time this relative positioning 10 of the parts has been effected, the plunger 23 will have been withdrawn and the air pressure valve 25 placed over the opening through which the plunger enters the neck and blank molds. A puff of air under pressure is then introduced into the 15 upper end of the blank mold resulting in compacting of the gathered mold charge against the walls of the blank mold and said closure cup 40. As a result of this operation the density of the blank is greatly increased and the lower end of 20 the charge which has been chilled and somewhat scarred by the cut-off knife, is to a very large degree reheated. Thus the scar is almost entirely eliminated. Exceptionally uniform distribution 25 of glass and a very appreciable improvement in the bottom formation of the finished articles of glassware result from following the above practice.

In Figs. 12 and 13 we have illustrated a novel means providing for adjustment of the cup holder 54 horizontally relative to the carrier 41. In this construction the arm 62 is pivoted by means of a vertical hinge pin 84 to an inverted channel iron bar 85. A pair of lock bolts 86 extending through slots 87 in said channel iron bar 85 slid-
30 ingly support said arm in contact with the lower side thereof. A pair of adjusting screws 88 are threaded into the side flanges of the channel iron bar 85 for engagement with the opposite vertical surfaces of the arm 62 on the holder 54. By
35 loosening the two lock bolts 86, the holder will be free for adjustment which is obtained merely by operating the adjusting screw 88. Because of the possibility of adjusting the holder as just brought out, it is evident that comparatively accurate alignment of the cup and corresponding mold may be obtained without necessitating any
40 relative movement between said cup and the re-
45 ceiver 53.

50 Modifications may be resorted to within the spirit and scope of the appended claims.

What we claim is:

55 1. In a glassware forming machine, the combination with a traveling frame of a suction blank mold having a downwardly facing charging opening, means for gathering a charge of molten glass from a receptacle into said mold, a charge sever-

ing device, means for temporarily closing the charging opening, said closing means including a horizontal carrier, means for reciprocating the carrier horizontally, an upwardly facing closure cup, a cup holder mounted at one end of the carrier, means whereby the cup holder may be adjusted about a vertical axis relative to the carrier, means for imparting vertical movement to the cup relative to said holder into sealing engagement with the mold, said holder including a vertical guide attached to the carrier, a telescopic extensible sleeve extending through the guide, a spring device normally tending to extend the sleeve, and a cam roll at the end of the sleeve opposite the cup.

2. In a glassware forming machine, the combination with a traveling frame of a suction blank mold having a downwardly facing charging opening, means for transferring a charge of molten glass from a receptacle into said mold, a charge severing device, means for temporarily closing the charging opening including an upwardly facing cup, a cup holder in which said cup is removably mounted, a pair of depending telescopic sleeves on the lower side of said cup holder, spring means tending to move the sleeves apart axially, a cam roll at the lower end of said sleeves, a vertical guide in which said sleeves are splined and axially reciprocable, means for bringing the cup, sleeves, and guide into register with the mold charging opening, and a cam positioned to engage said roller and effect yielding engagement between the cup and mold. 20 25 30

3. In a glassware forming machine, the combination with a traveling frame of a suction blank mold having a downwardly facing charging opening, means for transferring a charge of molten glass from a receptacle into said mold, a charge severing device, means for temporarily closing the charging opening including an upwardly facing cup, a cup holder in which said cup is removably mounted, a pair of depending telescopic sleeves on the lower side of said cup holder, spring means tending to move the sleeves apart axially, a cam roll at the lower end of said sleeve, a vertical guide in which said sleeves are splined and axially reciprocable, a horizontal carrier supporting the guide at one end, a piston motor operatively connected to the carrier for reciprocating the latter and periodically placing the cup in register with the mold charging opening, and a cam positioned to engage the roller and move the cup upwardly into engagement with the mold. 35 40 45 50
